UNITED STATES PATENT OFFICE

NORMAN L. BROCK, OF WEST BRIDGEWATER, MASSACHUSETTS

CUTTING DIE FOR PREPARING AND ORNAMENTING SHOE-UPPER MEMBERS

Application filed June 5, 1929. Serial No. 368,708.

This invention relates to a cutting-die used in forming ornamental edge portions on shoe-upper members, the die including an elongated knife and a holder therefor from which the cutting edge of the knife projects, the knife being formed to impart a predetermined contour to an edge of an upper member positioned on the knife and pressed against the cutting edge thereof.

Usually the die includes also tubular cutting punches arranged in a row parallel with the knife, and adapted to cut a row of holes in the blank while the knife is forming a finished edge thereon.

The chief object of the invention is to provide a die having means whereby it may be so adjusted that the contour of the end portions of the cutting edge of the knife may be varied to enable the die to form a finished edge, the end portions of which may have either of a number of different contours, so that a single die may be used in forming finished edges having differently contoured end portions.

Another object is to provide a die including both a knife and a row of punches, with means whereby the die may be so adjusted that the contour of the end portions of the cutting edge of the knife, and the contour of the ends of the row of punches, may be simultaneously varied, to enable the die to form a finished edge and a row of holes, the end portions of which may have either of a number of different contours, all producible by a single die.

Of the accompanying drawings forming a part of this specification,—

Figure 1 is a top plan view of a die embodying the invention.

Figure 2 is an edge view of the same.

Figure 3 is an end view.

Figure 4 is a perspective view of one of the pivoted knife-holder sections hereinafter described.

Figure 5 is a fragmentary section on line 5—5 of Figure 1.

Figure 6 is a fragmentary section on line 6—6 of Figure 1.

Figure 7 is a fragmentary section on line 7—7 of Figure 1.

Figure 8 is a fragmentary section on line 8—8 of Figure 12.

Figure 9 is a fragmentary section on line 9—9 of Figure 8.

Figure 10 is a fragmentary section on line 10—10 of Figure 1.

Figure 11 is a view similar to a portion of Figure 1, on a larger scale.

Figure 12 is a view similar to a portion of Figure 11, showing a different adjustment.

Figure 13 is a perspective view of the knife.

Figure 14 shows a portion of an upper member as completed by the knife and tubular punches.

The same reference characters indicate the same parts in all of the figures.

The knife element of my improved die, shown separately by Figure 13, is elongated and flexible, and includes a major or body portion 15 and end portions 16. The body portion may be of any form required by the design of the upper member 17, acted on by the die.

Figure 1 shows by dotted lines the entire outline of a vamp member 17 positioned on the die preparatory to being acted on thereby, and Figures 11 and 12 show by full lines, end portions of said member similarly positioned.

Figure 14 shows a portion of the member after it has been acted on by the die.

The knife-holding element of the die is composed of a body section 18, having means for fixedly confining the major portion 15 of the knife, and a pair of pivoted sections 19, having means for loosely confining the end portions 16. The body section 18 is fixed to a base 20, which, as shown by Figure 2, projects under and supports the pivoted sections 19, and constitutes, in effect, a part of the body section, although preferably separable therefrom. The pivoted sections 19 are mounted to swing horizontally on vertical pivot studs 21 engaged with the base and entering sockets formed for their reception in the pivoted sections. The pivoted sections are provided with curved slots 22 (Figure 4) in which the end portions 16 of the knife are inserted, the slots imparting curved contours to said end portions.

The pivoted sections have abutment faces 23 and 24, arranged to bear alternately on a face 25 on the body section 18, the arrangement being such that the pivoted sections may be positioned as shown by Figures 1 and 11, or as shown by Figure 12, or may occupy various intermediate positions, the positions of the knife end portions 16 relative to the major portion 15 being varied by each change of position of the pivoted sections. The knife end portions are loose in the slots 22, and are prevented from edgewise displacement therein by pins 26 (Figure 9) entering longitudinal slots 27 (Figure 13) in the end portions.

Each pivoted section 19 is preferably provided with a flange 190 (Figure 4), which is overhung by a holding-down flange on the body section, as indicated by Figure 1.

To permit the simultaneous adjustment of the pivoted sections and positively confine them in any position to which they may be adjusted, I provide adjusting means, preferably embodied in cylindrical studs 28, fitted to turn in sockets in adjacent swinging ends of the pivoted sections, a nut 30 having oppositely projecting arms 31, which are slidable in the studs 28, and an adjusting rod journaled in fixed bearings 32 and 33 (Figure 11), said rod having a screw-threaded portion 34, engaged with the nut 30, and a knob or handle 35, whereby it may be rotated.

The upper member 17, before it is acted on by the die, has a surplus edge portion which bears on the cutting edge of the knife and is positioned by spring-supported gage pins 36 (Figure 6), some of which are located on the body section, and others on the pivoted sections. When the upper member is thus supported, pressure is exerted on it to cause the knife to remove the surplus edge portion and thus form the finished edge portion shown by Figure 14. The knife may have a pinking cutting edge forming a pinked finished edge on the member 17.

The pivoted sections 19 may be provided with rows of tubular punches 37^a extending beside the slots 22 and forming continuations of a row of punches 37, with which the body section 18 is provided.

The usual spring-supported stripper plate with which a die of this character is provided, to force the work outward from the knife and punches, is provided in my improved die, in sections, there being a stripper plate section 38 associated with the body section, and stripper plate sections 38^a associated with the pivoted sections and movable therewith independently of the plate sections 38. Each stripper plate or section may be secured to studs 39, supported by springs 40 (Figure 5).

It will now be seen that the described cutting-die comprising an elongated flexible knife and a knife-holder having means for

flexing the end portions of the knife, is adapted to be adjusted to form on an article such as a vamp 17, an edge indicated by Figure 11, or an edge indicated by Figure 12, each adjustment causing the cut edge to have a different contour at its end portion, so that a single die may be employed to produce finished edges whose end portions have different contours.

The major or body portion 15 of the knife may be secured to the body section 18, by clamping it as indicated by Figure 10, between plates constituting a fixed top layer of the body section, and having knife-gripping edges 18^a (Figure 10) bearing on opposite sides of the knife. The slots 22 in the pivoted sections 19 receiving the end portions 16 of the knife, are provided, in this instance, by edges 18^b (Figure 8) of the plates constituting fixed top layers of the pivoted sections. Each holder section may include a hardened steel plate 18^c (Figures 8 and 10) on which the knife and the tubular punches bear.

To simplify the drawing, I have shown by Figure 1 only a portion of the stripper plate 38, the other stripper plates being omitted, all of the stripper plates being shown by Figures 2 and 3.

For the same reason, I have omitted the stripper plates from Figure 11, and have shown said plates in Figures 8 and 12. There is, of course, nothing new in the stripper plates, the plates or sections 38^a being adaptations of a well known stripper plate element to the pivoted knife-holder sections.

It is obvious that the form of the knife, and of the means securing the same to the body section and the pivoted section, may be variously modified. The knife here shown is adapted to form a deep throat in a vamp member.

As shown by Figure 8, the pivot stud 21 is tubular and its bore constitutes a portion of the clearance outlet of one of the tubular punches 37, the bore of said punch being in alignment with the bore of the pivot stud.

The die may be adapted to act on other shoe upper members, such as wing tips, quarters, and foxings.

It is to be understood that my invention is not concerned with parts shown by the drawings and not described herein.

I claim:

1. A cutting-die comprising an elongated flexible knife and a knife-holder including a body section having means for confining the major portion of the knife, and a pair of pivoted sections having means for confining the end portions of the knife, the pivoted sections being adjustable to flex said end portions and thereby vary the contour of an edge cut by the knife.

2. A cutting-die comprising an elongated flexible knife and a knife-holder including a

body section having means for confining the major portion of the knife, and a pair of pivoted sections having means for confining the end portions of the knife, the pivoted sections being adjustable to flex said end portions and thereby vary the contour of an edge cut by the knife, the fixed and pivoted sections being provided with rows of perforating punches arranged parallel with the knife, and adapted to cooperate therewith in producing ornamentation of variable contour.

3. A cutting-die comprising an elongated flexible knife and a knife-holder including a body section having means for confining the major portion of the knife, and a pair of pivoted sections having means for confining the end portions of the knife, the pivoted sections being adjustable to flex said end portions and thereby vary the contour of an edge cut by the knife, and means for simultaneously adjusting the pivoted sections and positively holding them in any positions to which they may be adjusted.

4. A cutting-die comprising an elongated flexible knife and a knife-holder including a body section having means for confining the major portion of the knife, and a pair of pivoted sections having means for confining the end portions of the knife, the pivoted sections being adjustable to flex said end portions and thereby vary the contour of an edge cut by the knife, and adjusting means embodied in studs fitted to turn in orifices in swinging ends of the pivoted sections, a nut having oppositely projecting arms slidable in transverse orifices in the studs, and an adjusting rod journaled in bearings on the fixed section and having a threaded portion engaged with the nut.

5. A cutting-die as specified by claim 1, the pivoted sections being provided with slots formed to receive and contour the end portions of the knife, said end portions being loose in the slots to permit swinging adjustments of the pivoted sections, means being provided for loosely confining the knife end portions in the slots.

6. A cutting-die as specified by claim 1, the pivoted sections being provided with slots formed to receive and contour the end portions of the knife, said end portions being loose in the slots to permit swinging adjustments of the pivoted sections, the end portions of the knife being provided with longitudinal slots which receive pins engaged with the pivoted sections, whereby the knife end portions are loosely confined in the slots.

7. An edge-ornamenting cutting-die comprising a holding structure including a body section and pivoted sections, adapted to have a swinging adjustment relative to the body section, and a flexible knife common to said sections and including a major portion engaged with the body section and end portions engaged with the pivoted sections.

8. An edge-ornamenting cutting-die comprising a holding structure including a body section and pivoted sections, adapted to have a swinging adjustment relative to the body section, a flexible knife common to said sections and including a major portion engaged with the body section and end portions engaged with the pivoted sections, and tubular punches forming a continuous row extending beside the knife, the punches constituting the ends of the row being carried by the pivoted sections.

9. An edge-ornamenting cutting-die comprising a holding structure including a body section and pivoted sections, adapted to have a swinging adjustment relative to the body section, a flexible knife common to said sections and including a major portion engaged with the body section and end portions engaged with the pivoted sections, and tubular punches forming a continuous row extending beside the knife, the punches constituting the ends of the row being carried by the pivoted sections, the pivoted sections being connected with the body section by tubular studs whose bores are in alinement with the bores of punches carried by the body section.

10. A cutting die comprising, in combination, a flexible cutting knife including a body portion and an end portion, and a knife-holder having fixed means engaging only the body portion of the knife to prevent flexure thereof and render invariable the contour of an edge cut thereby, and movable means engaging only the end portion of the knife and adjustable relative to the fixed means to flex the end portion and vary the contour of an edge cut thereby.

In testimony whereof I have affixed my signature.

NORMAN L. BROCK.
